(57) CLAIM

The ornamental design for “handle set for article of cookware”, as shown and described.

DESCRIPTION

FIG. 1 is a perspective view of “handle set for article of cookware” showing my new design;

FIG. 2 is a top view thereof;

FIG. 3 is a bottom view thereof;

FIG. 4 is a side view thereof;

FIG. 5 is another side view thereof;

FIG. 6 is a front view thereof; and,

FIG. 7 is a rear view thereof.

The part of the drawings shown in phantom lines depicts the environment of my new design and forms no part of the design.
